(57) **CLAIM**

I claim the ornamental design for a display case, as shown and described.

DESCRIPTION

FIG. 1 is a perspective view of a display case, showing my new design, with adjustable dividers thereof in a first position;

FIG. 2 is a front elevational view thereof;

FIG. 3 is a right side elevational view, the left side elevational view being a mirror image thereof;

FIG. 4 is a top plan view, the bottom plan view being a mirror image thereof;

FIG. 5 is a perspective view of the display case, with adjustable dividers thereof in a second position; and,

FIG. 6 is a front elevational view of the display case as it is shown in FIG. 5.

The rear of the display case is unornamented.
